UNITED STATES PATENT OFFICE.

DWIGHT S. RICHARDSON, OF NEW YORK, N. Y.

PRESSURE-GOVERNED REGULATOR.

1,075,380.

Specification of Letters Patent. Patented Oct. 14, 1913.

Application filed October 28, 1912. Serial No. 728,211.

To all whom it may concern:

Be it known that I, DWIGHT S. RICHARDSON, a citizen of the United States, residing at New York, in the county and State 5 of New York, have invented certain new and useful Improvements in Pressure-Governed Regulators; and I do hereby declare the following to be a full, clear, and exact description of the same, reference being had 10 to the accompanying drawings, forming part of this specification, and to the figures and letters of reference marked thereon.

This invention relates to pressure governed regulators, especially of that type designed for operating dampers of steam or similar heating plants, the objects of the invention being to provide a highly efficient and exceedingly simple regulator which will withstand relatively high pressures, and 15 not be subject to deterioration from a corrosive or chemical action of the fluid with which it may be brought into contact, or which serves as the pressure medium for operating the regulator.

20 The invention consists in certain novel details of construction and combinations and arrangements of parts all as will be hereinafter described and pointed out particularly in the appended claims.

25 Referring to the accompanying drawings: Figure 1 is a sectional elevation of a damper regulator embodying the present improvement. Fig. 2 is a top plan view of the same with portions broken away and in 30 section to illustrate certain features of construction. Fig. 3 is a section in a horizontal plane indicated by the line 3—3 of Fig. 1. Fig. 4 is a perspective view of the upper portion of the preferred form 35 of confining casing and damper lever support. Fig. 5 is a perspective view of the preferred form of plunger for operating the damper lever. Fig. 6 is a detail section illustrating the preferred means of connecting the bellows or expansible member with the bottom of the supporting and confining casing.

Like letters of reference in the several figures indicate the same parts.

40 Regulators of the general type to which the present invention relates and the manner of mounting the same and connecting the operated parts with the furnace damper or other device to be operated by the 45 regulator, are well known. In illustrating the present invention, it has, therefore, been

thought unnecessary to show more than those parts in which the present improvements reside, and the parts immediately associated therewith, for example, the pivoted lever A, shown in Figs. 1 and 2, is the part which is to be connected by well known mechanical connections with the damper or ultimate device to be operated, and the hub or boss B internally threaded 50 is adapted to be connected to a suitable pipe, (which may also support the regulator) leading from a source of pressure supply, as a steam boiler, in which the pressure is liable to fluctuate and by which 55 fluctuations the damper is to be operated. The hub or boss B is preferably formed as an integral part of a base plate B', which in general contour is preferably circular, but has projecting from its periphery, a 60 plurality, preferably three, equally spaced lugs or ears B². In the upper face of the plate B' is an annular groove formed by an upwardly extending peripheral flange b' and an internal flange spaced from the 65 flange b' and of somewhat less height. The two flanges are preferably continuous around the entire plate B' and the lugs B² are outside of the flange b.

70 Resting on the lugs B² and with their 75 lower edges in seats therein are three upwardly extending legs or supports C' for a top plate or cover C. The top plate or cover C and the legs C' are preferably formed in an integral casting, as shown in 80 Fig. 4, the legs being of semi-cylindrical form, as shown in section in Fig. 3, and the cover plate C being provided with a downwardly extended peripheral flange c arranged opposite the flange b on the bottom plate. The two plates C and B' are 85 connected to form a rigid inclosing casing or structure by bolts D which pass down through the legs C' and have at their lower ends nuts d seating in recesses d' in the 90 under faces of the lugs B², whereby their 95 rotation will be prevented and whereby the bolts may be tightened by a screw driver applied to the usual slot or neck in their heads or upper ends. This construction is 100 one which is not liable to separate or loosen up under conditions of use, and one competent to withstand a considerable internal 105 pressure.

The flanges b and c and the inner edges 110 of the semi-circular legs C' form a cylindrical chamber, as it were, with relatively large

2

spaces in its walls between the legs and flanges, and in this chamber there is located a cylindrical expansible and collapsible vessel or bellows. This expansible and collapsible vessel is preferably formed of sheet metal with its peripheral walls deeply corrugated, as at E, whereby said walls are permitted a wide range of expansion or contraction, vertically, but are competent to resist relatively high lateral pressure without injurious lateral deformation, except such as may be incident to the vertical expansion and contraction. The circular corrugated wall E of the vessel is confined within the chamber formed by the flanges c and b and the legs C', so that even under excessive pressure adequate lateral support will be afforded and accidental bursting prevented under extreme and unusual conditions. The lower edge of the corrugated wall E is united to the base plate B' within the annular groove formed by the flanges b and b', the method of connecting these parts being preferably to fill the groove with solder, and after the lower edge of the wall E has been suitably prepared by tinning, the solder in the groove is heated or melted and the said edge inserted in the solder-filled groove. The plate B' may be placed on a suitable heater for this purpose, and usual soldering appliances such as a heavy soldering iron employed to complete the operation in accordance with known shop practice, but it is preferred that the lower edge of the wall E be provided with an offset or groove such as indicated at b², which may be filled by the body of solder, so as to effectually anchor the vessel and overcome any possible danger of separation at the joint or point of union. The vessel formed by the wall E is provided with a top plate or closure which at its periphery is seamed or otherwise united to the upper edge of the wall E, as indicated at f, and the central portion of the closure is dished or formed into a well with rounded lateral walls as indicated at F in Fig. 1, there being an upwardly projecting bead f' which is adapted to contact with the confining top plate C of the casing for limiting upward expansion of the vessel.

The central well F in the top closure of the vessel is located immediately beneath a central opening H in the casing top C, and is adapted for the reception of the rounded lower end or portion i' of a plunger I, which extends upwardly above the cover C and is pivotally connected at K with the lever A. The lever A is pivotally mounted between the bifurcated ends of an upwardly extending lug L on the top C, and the pivotal connection of the lever with the plunger I is also preferably formed by passing said lever through a slot k in the plunger as best seen in Fig. 2, and uniting the parts by a transverse rivet or bolt. With this arrangement

ment the head of the plunger I is located within the chamber and in assembling the parts the plunger is placed into position before the cover, base and vessel are assembled, and consequently is not liable to be displaced or lost should unskilled labor remove the operating lever A for any purpose. An additional advantage in this particular construction is due to the possibility of providing a cheap and convenient means whereby the inward movement of the plunger may be limited so as to prevent the expansible vessel from being injuriously collapsed, more especially during periods when there is no internal pressure. This result is accomplished by forming lateral lugs M on the plunger in such position that they will seat against the top C when the plunger has reached the desired downward limit of its movement, and for assembling the parts the opening in the top C is provided with the lateral enlargement h through which the lugs M may pass, but the relation of the enlargements h, lugs M and slots k is such that when the plunger is turned into position to receive the lever A, the lugs M will be out of alignment with the enlargements h, as shown clearly in Fig. 2, and therefore cannot pass down through the opening.

In practically all devices of this type difficulty in maintenance has been experienced, due to the fact that for long periods of time the chamber is subjected to corrosive or chemical action of the pressure fluid and as such action is usually most manifest in the iron which forms the bottom of the chamber, special provision must be made to prevent or overcome the effect. The present construction lends itself most favorably to a simple means for accomplishing this end, inasmuch as the inner face of the bottom of the chamber is left free from any working parts, and said bottom may, therefore, be plated with a non-corroding metal, which plating will extend from the corrugated wall down into the intake opening.

In the preferred construction, the bottom B' is electro copper plated, as indicated by the heavy surface line at B'. It is then tinned around the bottom in the groove before referred to so as to more effectually hold the solder when the groove is filled with solder as described.

Having thus described my invention, what I claim as new and desire to secure by Letters Patent of the United States, is:

1. In a regulator such as described, the combination with a bottom plate having the pressure supply connection therein, a peripheral flange and lugs extending beyond said flange, a top plate having a peripheral flange and downwardly extending legs adapted to seat on the lugs of the bottom plate, said top plate having also a central opening and a lever support at one side

- of said opening, and means for rigidly connecting the top and bottom plates together, of an expansible vessel mounted between the top and bottom plates, said vessel having a corrugated peripheral wall, an inwardly dished top, and having its lower edge permanently connected with the bottom plate within the peripheral flange, a plunger extending through the opening in the top plate and having an enlarged head loosely mounted in the dished portion of the vessel, and a lever pivotally connected with the plunger and lever support, respectively.
- 15 2. In a regulator of the type described, the combination with a bottom plate having the pressure supply connection therein, two upwardly projecting peripheral flanges forming a groove between them, the outer flange being of greater height than the inner flange and lugs projecting beyond said flanges, a top plate having a peripheral flange and downwardly extending legs seated on the lugs on the bottom plate, said 20 top plate having a central aperture and a lever support at one side of said aperture, and means for rigidly connecting the top and bottom plates to form an inclosing casing, of a vessel mounted within said casing, and having a corrugated peripheral wall and inwardly dished top, the lower edge of said vessel being permanently united to the bottom plate by a body of soft metal confined between the peripheral flanges, a plunger 30 having an enlarged head resting in the dished top of the vessel and projecting through the opening in the top plate and a lever pivotally connected with the plunger and lever support, respectively.
- 35 3. In a regulator of the type described, the combination with the bottom plate having the pressure supply connection therein, the top plate spaced from the bottom plate, rigidly connected thereto, and having a central opening with a transverse enlargement, and an upwardly extending lever support, of an expansible vessel having its 40 lower edge permanently connected with the bottom plate and having its upward expansion limited by the top plate, a plunger having an enlarged head resting on said vessel, the stem of said plunger extending upwardly through the opening in the top plate and having a transversely projecting lug thereon, whereby the parts may be assembled by 45 passing said stem and lug through the opening and its enlargement, a lever pivotally mounted in the lever support, and a pivotal connection between said lever and plunger arranged to position the lug at one side 50 of the transverse enlargement of the stem opening, whereby the downward movement of the plunger will be limited by the co-operation of the lug with the top plate.
4. In a regulator of the type described, the combination with the bottom plate having the pressure supply connection therein and upwardly extending peripheral flanges forming a groove between them, the outer flange being of greater height than the inner flange, there being peripheral lugs 55 equally spaced on the outer side of the outer flange, a top plate having a downwardly extending peripheral flange and legs integral with the top plate seating on the 60 lugs on the bottom plate, said legs and flanges forming a substantially cylindrical confining chamber with wide spaces between the legs and between the flanges, and bolts extending through the legs for rigidly connecting the top and bottom plates, of a cylindrical vessel located within the flanges and between the plates, the peripheral wall of said vessel being transversely corrugated and with its lower edge permanently confined in the groove between the flanges on the bottom plate, a plunger resting on said vessel and extending loosely through the top plate, and an operating lever pivotally connected with said plunger.
